UNITED STATES PATENT OFFICE

2,488,753

AUTOMATIC DRAFT CONTROL FOR GRAIN DRIERS

Albert B. Welty, Moline, Ill., assignor to International Harvester Company, a corporation of New Jersey

Application December 22, 1945, Serial No. 636,885

11 Claims. (Cl. 263—29)

1

This invention relates to a new and improved automatic draft control for grain dryers and has for one of its principal objects the provision of means for regulating the draft for furnaces used in conjunction with grain dryers.

An important object of this invention is to provide a valve positioned between a furnace and a source of suction and operable responsive to the amount of draft within the furnace.

Another important object of the present invention is to provide an automatic valve operating means to control furnace draft in the grain dryer set forth in my copending application entitled "Suction type grain dryer" which has now issued as Patent No. 2,437,899.

As described in my copending application mentioned above, I employ an oil burning furnace for the source of heat necessary to dry the grain. It is common knowledge that furnaces require a draft in order that combustion take place. Usually a furnace is supplied with a stack or chimney which naturally creates sufficient draft to support combustion. However, in conjunction with my grain dryer it is practically impossible to employ a stack comparable to those used in homes or buildings, and hence it is necessary to artificially create the draft ordinarily created by a tall chimney. In my grain dryer I employ a suction fan to draw heated air up through a column of grain in order to cause drying of the grain. As shown in my earlier filed case on the entire grain dryer, I employ this same suction fan to create draft for my oil burning furnace. A manually operable valve is shown and has been described in my prior case for regulating the amount of suction to be applied to the furnace flue. It is therefore an object of the present case to provide an automatically operable valve for regulating the amount of draft to be applied to the furnace and directly responsive to the condition within the furnace.

Other and further important objects may become apparent from the following specification and accompanying drawings, in which:

Figure 1 is a vertical sectional view of my grain dryer showing the automatically operable draft valve incorporated therein and taken on the line 1 of Figure 3;

Figure 2 is an enlarged view of the automatically operable draft valve as shown in Figure 1; and

Figure 3 is a sectional view taken on the line 3—3 of Figure 2.

As shown in the drawings:

Reference numeral 10 indicates generally a

5 grain dryer or dehydrating chamber. The chamber 10 is enclosed within insulated walls 11 and 12 and in the bottom thereof is equipped with plenum chambers 13, 14, and 15. The plenum chambers communicate directly with a source of heat created in this particular instance by an oil burning furnace. Screened apertures are provided at 16 and 17, 18 and 19, and 20 and 21 in the plenum chambers 13, 14 and 15 respectively. The chamber 10 is adapted to be filled with grain to be dried. The intake for the grain is at the top of the chamber through a conduit 22 which has spaced apertures in the bottom along the entire length thereof. An auger conveyor 23 is adapted to be rotated within the conduit 22 and feeds the grain to be dried therealong. When the grain dryer is in full operation the chamber 10 is entirely filled with grain, forming a substantial column of grain to be dried. The grain 10 is discharged from the chamber 10 by a plurality of rolls 24, 25, 26, and 27 extending longitudinally of the chamber 10 and between and at the sides of the plenum chambers 13, 14, and 15. Each of the discharge rolls 24, 25, 26, and 27 have 15 pockets in the periphery thereof at 28, 29, 30, and 31, respectively, for reception of a predetermined quantity of dried grain. Upon rotation of the rolls the grain is dropped out of the pockets on the underside and into a compartment 32 beneath the plenum chambers and rolls. An auger conveyor 33 is positioned lengthwise of the compartment 32 and carries the dehydrated grain to one end of the grain chamber 10 from which point it is elevated or otherwise carried to storage bins.

20 As best shown in Figure 2, the flue gases are drawn upwardly through a furnace radiator. The purpose of the furnace radiator is to pass hot flue gases through a plurality of conduits within and adjacent the grain in the heating chamber so that the major portion of the heat within the gases being discharged are transferred to the grain to be dried, thus effecting efficient furnace operation. A tubular conduit 35 extends the length of the grain chamber 10 and is shown 25 in my copending application mentioned above. The conduit 35 discharges its flue gases into the outer hexagonal chamber 36. This hexagonal chamber 36 is adapted to carry the flue gases back through the length of the grain chamber 10 and discharges the exhaust gases through the conduit 37. A butterfly valve 38 is pivoted for rotational movement on a shaft 39 journaled within the conduit 37, as best shown in Figure 2. A suction fan is provided at one end of the

grain chamber 10 and is positioned within the circular housing 40 as best shown in Figures 1 and 3. The primary function of the suction fan is to draw hot air created by a furnace (not shown) upwardly through the plenum chambers 13, 14, and 15 through the column of downwardly discharging grain and out up over the top of the column of grain to the fan housing 40 where it is exhausted through the large conduit 41. The path of hot air travel is indicated by 10 arrows 50 in Figure 3.

A second function of the suction fan is to provide draft for the furnace which supplies the heat for this grain dryer. If the flue gases were merely 15 exhausted to atmosphere through conduit 37, there would not be sufficient draft to maintain combustion in the furnace. Hence communication is provided between the furnace and the suction fan to draw the flue gases up through the furnace radiator and the conduits 35 and 36 20 where they are exhausted through the conduit 37, as indicated by the arrows 51, joining with the suction fan stream of air indicated by the arrows 50. The amount of suction created by the fan is not always constant and hence the butterfly valve 38 must be opened or closed, more or less depending on the amount of suction and also depending on the amount of draft necessary to cause the furnace to burn efficiently.

The butterfly valve shaft 39 extends downwardly through the conduit 37 and has fixedly mounted on the end thereof an arm 42. The outer end of the arm 42 is joined by a link 43 to an upwardly extending arm 44 of a bell-crank lever 45. The bell-crank lever 45 is pivoted at 46 on a bracket 52 fixedly attached to a partition wall 53. A downwardly extending arm 47 of the bell-crank 45 is adapted to swing within predetermined limits fixed by adjustable set screws 48 and 49. These set screws 48 and 49 40 threadedly engage ears 54 and 55, respectively, bent outwardly from the bracket 52. A rod-like link is pivotally attached to the lower end of the arm 47 and is attached at its other end at 57 to a lever arm 58. The lever 58 is pivoted at 59 on a fixed bracket 60 rigidly attached to the wall 11. A pressure responsive element such as a diaphragm or bellows 61 is positioned within a compartment 61^a on the side of the grain chamber and has a rearwardly extending post 62 pivotally attached to the lever arm 58 at 63 spaced upwardly from the pivotal attachment 59 of the lever arm 58.

A small tube 64 joins the furnace radiator at 65 and the compartment 61^a on one side of the diaphragm or bellows at 66. The diaphragm 61 is provided with a chamber in the front thereof so that draft or suction within the furnace radiator may directly act on the diaphragm 61. If the draft within the furnace radiator 34 is relatively strong, the diaphragm 61 will be pulled inwardly toward the wall 11 of the grain chamber. A pulling of the diaphragm 61 causes a movement of the rod 56 and thus a clockwise movement of the bell-crank lever 45 as viewed in Figure 2. Such a clockwise movement of the bell-crank lever 43 causes the butterfly valve 38 to pivot about its axis shaft 39 closing the opening in the conduit 37 between the furnace radiator and the suction fan chamber 40. The draft or suction within the furnace radiator is then decreased and the movement or action on the diaphragm 61 is proportionately decreased.

A spring 67 is anchored at one end to the wall 11 at 68 and at its other end is attached to an 75 means in said conduit for varying the amount

upwardly extending lug 69 at 70. The lug 69 forms part of a clamp member 71 fixedly attached to the rod member 56. The spring 67 normally exerts a force in an outward direction on the rod 56 so that the lever arm 58 tends to move toward its outer casing 72. The spring 67 may have its tension adjusted by tightening or loosening of the lock nuts 73. The suction within the furnace radiator 34 must be sufficient to overcome the action of the spring 67, and when as previously described the butterfly valve 38 is partially closed by movement of the diaphragm 61, the decreased draft within the radiator causes a releasing of the hold on the diaphragm 61 so that it is partially overcome by a counteraction of the spring 67 which tends to cause movement of the bell-crank lever 45 in a counterclockwise direction resulting in an opening of the butterfly valve 38. The strength of the spring 67 is so adjusted that the valve 38 will assume a position most favorable to complete efficient combustion in the furnace.

Numerous details of construction may be varied over a wide range without departing from the principles disclosed herein and I therefore do not propose limiting the patent granted hereon otherwise than as necessitated by the appended claims.

What is claimed is:

1. In a suction type grain dryer having a furnace and a suction fan adapted to draw hot air from the furnace upwardly through a column of grain, a furnace flue gas radiator in said column of grain, a conduit joining said radiator with said suction fan, valve means in said conduit for varying the amount of passage opening between said radiator and said suction fan, and means responsive to the draft in the furnace radiator for controlling said valve means to control the amount of suction applied to the furnace radiator.

2. In a suction type grain dryer having a furnace and a suction fan adapted to draw hot air from the furnace upwardly through a column of grain, a furnace flue gas radiator in said column of grain, a conduit joining said radiator with said suction fan, valve means in said conduit for varying the amount of passage opening between said radiator and said suction fan, and means responsive to the draft in the furnace radiator for controlling said valve means, said means comprising a pressure actuated device associated with the radiator and directly effecting the position of the valve means by the strength of draft within the radiator.

3. In a suction type grain dryer having a furnace and a suction fan for drawing furnace hot air upwardly through an enclosed column of grain, a furnace flue gas radiator positioned in said column of grain for effecting heat transfer to said grain, a conduit joining said radiator with said suction fan, valve means in said conduit for varying the amount of passage opening between said radiator and said suction fan, means responsive to the draft in the furnace radiator for controlling said valve means, said means comprising a pressure responsive diaphragm communicating with said radiator, and linkage operatively joining said valve means and said diaphragm, whereby movement of the diaphragm will cause movement of said valve means.

4. In a suction type grain dryer having a furnace and a suction fan for drawing heat through a mass of grain, a furnace flue gas radiator positioned within said mass of grain, a conduit joining said radiator with said suction fan, valve means in said conduit for varying the amount

of passage opening between said radiator and said suction fan, means responsive to the draft in the furnace radiator for controlling said valve means, said means comprising a pressure responsive diaphragm, linkage operatively joining said valve means and said diaphragm, spring means adapted to normally act against said diaphragm tending to open said valve means, and a conduit extending between said furnace radiator and said diaphragm, whereby an increased draft within the furnace radiator tends to close said valve means against the action of the spring means.

5. In a suction type grain dryer having a furnace and a suction fan for carrying heat from the furnace through a mass of grain, a furnace flue gas radiator placed in said mass of grain for more efficient grain heating, a conduit joining said radiator with said suction fan, valve means in said conduit for varying the amount of passage opening between said radiator and said suction fan, means responsive to the draft in the furnace radiator for controlling said valve means, said means comprising a pressure responsive diaphragm, linkage operatively joining said valve means and said diaphragm, spring means adapted to normally act against said diaphragm tending to open said valve means, a conduit extending between said furnace radiator and said diaphragm, whereby an increased draft within the furnace radiator tends to close said valve means against the action of the spring means, and adjustable limits for said valve means whereby the limits may be adjusted so as not to permit complete opening or closing of the valve means.

6. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of heat exchange conduits positioned within the grain drying chamber, conduit means joining said furnace radiator with said suction fan, valve means within said conduit means for varying the amount of passage therethrough, and automatic means for controlling said valve means responsive to the draft within the furnace radiator.

7. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of heat exchange conduits positioned within the grain drying chamber, conduit means joining said furnace radiator with said suction fan, valve means within said conduit means for varying the amount of passage therethrough, automatic means for controlling said valve means responsive to the draft within the furnace radiator, said automatic means including a compartment having a pressure responsive element therewithin, a conduit joining said furnace radiator with the compartment on one side of the pressure responsive element, and linkage means joining said valve means with said pressure responsive element, whereby the valve means is controlled by movements of the pressure responsive element.

8. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of

heat exchange conduits positioned within the grain drying chamber, conduit means joining said furnace radiator with said suction fan, valve means within said conduit means for varying the amount of passage therethrough, automatic means for controlling said valve means responsive to the draft within the furnace radiator, said automatic means including a compartment having a diaphragm therewithin, a conduit joining said furnace radiator with the compartment on one side of the diaphragm, and linkage means joining said valve means with said diaphragm, whereby the valve means is controlled by movements of the diaphragm.

9. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of heat exchange conduits positioned within the grain drying chamber, conduit means joining said furnace radiator with said suction fan, valve means within said conduit means for varying the amount of passage therethrough, automatic means for controlling said valve means responsive to the draft within the furnace radiator, said automatic means including a compartment having a diaphragm therewithin, a conduit joining said furnace radiator with the compartment on one side of the diaphragm, linkage means joining said valve means with said diaphragm, and adjustable spring means associated with said diaphragm for normally tending to open said valve means, whereby the valve means is closed proportionately to the amount of draft within the furnace radiator sufficient to overcome the action of the spring means.

10. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of heat exchange conduits positioned within the grain drying chamber, conduit means joining said furnace radiator with said suction fan, valve means within said conduit means for varying the amount of passage therethrough, automatic means for controlling said valve means responsive to the draft within the furnace radiator, said automatic means including a compartment having a diaphragm therewithin, a conduit joining said furnace radiator with the compartment on one side of the diaphragm, linkage means joining said valve means with said diaphragm, adjustable spring means associated with said diaphragm for normally tending to open said valve means, whereby the valve means is closed proportionately to the amount of draft within the furnace radiator, and adjustable limit means associated with said linkage for limiting valve movement.

11. In a suction type grain dryer having a furnace and a suction fan, a grain drying chamber positioned between said furnace and suction fan, whereby heat is drawn from the furnace by the fan through the grain in the drying chamber, a furnace flue gas radiator having a plurality of heat exchange conduits positioned within the grain drying chamber, conduit means joining said furnace radiator with said suction fan, butterfly valve means within said conduit means for varying the amount of passage therethrough, automatic means for controlling said valve means re-

sponsive to the draft within the furnace radiator, said automatic means including a compartment outside said grain chamber having a diaphragm therewithin, a conduit joining said furnace radiator with the compartment on one side of the diaphragm, linkage means joining said valve means with said diaphragm, adjustable spring means associated with said diaphragm for normally tending to open said valve means, whereby the valve means is closed proportionately to the amount of draft within the furnace radiator, and adjustable limit means associated with said linkage for limiting valve movement.
